UNITED STATES PATENT OFFICE.

EDGAR L. MANTOR, OF LITCHFIELD, MINNESOTA.

WASHING-MACHINE.

SPECIFICATION forming part of Letters Patent No. 341,258, dated May 4, 1886.

Application filed December 4, 1885. Serial No. 184,725. (No model.)

To all whom it may concern:

Be it known that I, EDGAR L. MANTOR, a citizen of the United States, and a resident of Litchfield, in the county of Meeker and State 5 of Minnesota, have invented certain new and useful Improvements in Washing-Machines; and I do hereby declare that the following is a full, clear, and exact description of the invention, which will enable others skilled in the 10 art to which it appertains to make and use the same, reference being had to the accompanying drawings, which form a part of this specification, and in which—

Figure 1 is a perspective view of my improved 15 washing-machine, showing the rubber swung out of the suds-box. Fig. 2 is a longitudinal vertical section of the machine, and Fig. 3 is a perspective view of one of the slats of the rubber.

Similar letters of reference indicate corresponding parts in all the figures.

My invention has relation to reciprocating-rubber washing-machines; and it consists in the improved construction and combination of 25 parts of the same, as hereinafter more fully described and claimed.

In the accompanying drawings, the letter A indicates the rectangular suds-box, which is preferably mounted upon legs B, and the bottom 30 of which is provided with a slat bottom, C, consisting of two longitudinal bars, D, to the upper sides of which the cross-slats E are secured with intervals between them, the upper sides of these cross-slats being rounded, 35 while the lower faces of the slats are flat, bearing upon the longitudinal bars. One end of the slat bottom is held in place by means of a lug or cleat, F, and the other end of the bottom is secured by means of hooks and staples 40 G, and it will be seen that this end may be released, and the other end, which is inserted under the cleat, may be withdrawn after the hooked end has been raised.

The rubber consists of two arms, H H, pivoted at their ends upon a rod, I, secured near the upper edges of the side pieces, near one end of the suds-box, and to the free ends of these arms and to points near their inner ends are pivoted, respectively, a pair of levers, J J, 50 and a pair of links, K. The upper ends of the levers, the lower portions of which are as long as the downwardly-pending arms K, are

connected by means of a handle, L, and the lower ends of the levers and of the arms are connected by means of pivotal bolts or rods 55 M, which pass through the ends of the serrated slats of the rubber N. These slats O have their lower edges curved at the ends and serrated throughout their entire length, and the slats are placed with narrow spaces between them, so as to allow free passage for the suds or air when the machine is operated.

The horizontal arms may be tilted back out of the suds-box when not in use, the rubber being tilted with it, and the rubber will drop 65 downward when the arms are tilted back, its gravity drawing it downward, and the pivoted levers and arms allowing it to drop into position between the backwardly-tilted horizontal arms, as shown in Fig. 1.

It will be seen that, the clothes resting upon the flat slat bottom of the suds-box, the clothes will be raised above all impurities which may settle in the bottom of the suds-box, and which will drop between the slats of the false bottom, 75 and the slats, being rounded upon the upper sides, will serve to rub the dirt out of the clothes when the clothes are reciprocated in the suds-box by means of the rubber, which may be reciprocated by rocking the levers. 80

The serrated edges of the slats in the rubber will rub the clothes, and the suds and water and air may pass through the spaces between the slats of the rubber, thus allowing free circulation of suds and air in the suds-box, while 85 the serrations of the lower edges of the slats are rounded, so as not to tear the clothes.

The slat bottom being flat, the clothes are not so liable to be rolled into a ball or bundle as they are in washing-machines having a 90 rounded bottom, the reciprocating rubber spreading the clothes over the entire flat bottom, the sled-shaped ends of the slats obviating any tendency of the rubber to roll up the clothes as it passes over them.

The rubber may be accommodated to any thickness of the layer of clothes in the suds-box, the horizontal arms swinging upward as the thickness of the layer is increased, and the arms will in this manner allow the rubber to 100 be reciprocated at any desired height within the box.

When the clothes have been rubbed sufficiently the rubber may be swung out of the

box by the swinging arms, and the slat bottom may be taken out after the clothes have been removed, allowing any sediment to be removed from the bottom of the suds-box.

- 5 I am aware that rubbers for reciprocating-rubber washing-machines have been constructed of slats secured together with spaces between them, and do not claim such construction, broadly; but
- 10 I claim and desire to secure by Letters Patent of the United States—

The combination of a flat-bottomed suds-box, a flat rubber, a pair of levers pivotally

secured to one end of the rubber and connected at their tops by a handle, a pair of links 15 pivoted at the other end of the rubber, and a pair of arms pivotally secured to said levers and links and to the sides of the suds-box, substantially as described and set forth.

In testimony that I claim the foregoing as 20 my own I have hereunto affixed my signature in presence of two witnesses.

EDGAR L. MANTOR.
